UNITED STATES PATENT OFFICE.

WINSLOW EDGAR HINSON, OF FORT SMITH, ARKANSAS.

CABINET.

Application filed January 5, 1924. Serial No. 684,638.

The device forming the subject matter of this application is a cabinet adapted to be mounted on the running board of an automobile, and so constructed that it may be applied to the running board on either side of the vehicle, the device being so constituted that it will not come into contact with the body of the automobile to the damage of the latter. Another object of the invention is to provide a cabinet which can be opened readily; and which will be so constructed that it will be rain-proof, it being possible to use the cabinet in connection with a tent connected to the automobile.

It is within the province of the disclosure to improve generally and to enhance the utility of devices of this type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown, can be made, without departing from the spirit of the invention.

In the drawings:—

Figure 1 shows in elevation a device constructed in accordance with the invention; Figure 2 is a front elevation; Figure 3 is a vertical transverse section; Figure 4 is a vertical longitudinal section.

The cabinet forming the subject matter of this application includes a body 1, preferably made of metal and comprising sides 2 and a back 3, the back 3 being inclined upwardly and forwardly as at 4 to form a recess, the purpose of which will be made manifest hereinafter. The bottom 5, which may be made of wood, is located within the body 1 at the lower end thereof and is secured in place in any desired way. The bottom 5 may carry bolts 6 or the like, shown in Figure 1 only, whereby the bottom may be secured to the running board of an automobile. It is to be understood, however, that any sort of fastening means may be substituted for the bolts 6. The lower edge of the front 7 of the cabinet is connected by hinges 8 to the bottom 5 and is adapted to swing downwardly and outwardly. In order to render the device rain-proof, the back 3 and the front 7 may be provided with

flanges 9 overlapping the sides 2. The front 7 carries a button or handle 10 whereby the front may be manipulated readily on the hinges 8. One or more flexible elements 11 are connected at their forward ends to the front 7. The sides 2 carry hooks 12 or the like adapted to engage the flexible elements 11, so that the front 7 may be swung downwardly and outwardly, toward an open position, to any desired extent. Any desired number of vertically spaced shelves 14 are located within the body of the cabinet and have upstanding flanges 15 connected by securing elements 16 with the sides 2 of the cabinet. A vertically swinging lid 17 is hinged at 18 to the back 3 and has flanges 19 overlapping the sides 2 and overlapping the upper edge of the front 7 for the double purpose of preventing water from finding its way into the cabinet, and for holding the front 7 against downward swinging movement from the position shown in Figure 3. The lid 17 has a slight slant as indicated at 20, at its point of connection with the back 3, from one end of the cabinet to the other. Suppose that the vehicle on which the cabinet is mounted, is proceeding in the direction indicated by the arrow A in Figure 2. Most of the rain which falls on the lid 17 tends to run off transversely of the lid, as indicated by the arrow B in Figure 1: but although the major portion of the rain tends to run off transversely, as shown by the arrow B in Figure 1, there is a small but constantly increasing amount of water that tends to move lengthwise of the lid, and to run off the rear end C of the lid, and to fly into the vehicle. Because the rear edge of the lid 17 has a slant, as shown at 20, the rear inner corner D of the lid is higher than the forward corner E of the lid, and the water that flows longitudinally of the lid, as hereinbefore mentioned, tends to follow the course indicated by the arrows F in Figure 2 and to run off the lower edge G of the lid, rather than off the rear end C of the lid and into the vehicle.

The device forming the subject matter of this application may be mounted readily on the running board of an automobile, and by opening the front access may be had to the objects in the cabinet and on the shelves 14, the chains or flexible elements 11 cooperating with the hooks 12, to afford a means where-

by the front 7 may be held in any position to which it may have been opened. The front 7 is held closed by the flange 19 on the lid 17. When the lid 17 is swung upwardly, the front 7 is released, and may be swung downwardly toward an open position on the hinges 8. The flexible elements 11 may be so adjusted on the hooks 12 so as to hold the front 7 closed, and, then access may be had to the space above the uppermost shelf 14 by merely opening the lid 17. As shown at 4, the back 3 is so curved and shaped as to conform to the outward bulge in the automobile. The maximum amount of space is provided in the cabinet, since the cabinet is wider at its lower portion than at its top, and because the back 3 is shaped as indicated at 4, the cabinet may clear the body of an automobile, it being possible to mount the cabinet on the running board without scratching the body. The cabinet may be turned end for end and be used on either the right hand running board of an automobile or the left hand board thereof.

In order to hold the lid 17 closed, a hook 50 may be pivoted to one of the flanges 19 of

the lid, the hook being adapted to engage a keeper 51 on the side 2 of the body 1.

Having thus described the invention, what is claimed is:—

A cabinet comprising a bottom, sides, and a back, a front hinged at its lower edge to the bottom, a top hinged at its rear edge to the upper edge of the back, the upper edge of the front and the forward edge of the top being interengaged, the forward edge of the top being parallel to the bottom of the cabinet, the rear hinged edge of the top slanting lengthwise of the cabinet from one of the sides of the cabinet to the other, the top also slanting downwardly and forwardly from the upper edge of the back to the upper edge of the front, and means for mounting the cabinet on the running board of an automobile with the slanting rear edge and the top so located as to deflect rain from flying off the top into the automobile whereon the cabinet is mounted.

In testimony that I claim the foregoing as my own, I have hereto affixed my signature.

WINSLOW EDGAR HINSON.
